UNITED STATES PATENT OFFICE

FRANKLIN S. SPEICHER, OF PITTSBURGH, PENNSYLVANIA, ASSIGNOR TO M. E. CUNNINGHAM COMPANY, A CORPORATION OF PENNSYLVANIA

DIE

Application filed February 2, 1932. Serial No. 590,453.

The invention relates to dies or embossing devices designed particularly for the making of automobile plates but useful in other relations and for a wide variety of work. It has for its objects the provision of an improved construction in which the die parts are pivoted together, so that their relative position is positively established, but which permits the dies to approach in parallelism during the actual stamping operation. Further objects are; (1) the provision of a construction in which the strain imposed on the pivot is practically negligible, so that there is little wear at this point; (2) which requires no guiding means, aside from the hinge connection between the die holders; and (3) in which any tendency to impart movement to the plate being stamped in its own plane is toward the gage or stop means between the dies and pivots, so that the blank is maintained against any displacement incident to the stamping operation. One embodiment of the invention is shown in the accompanying drawings, wherein:

Figure 1 is a plan view of the apparatus (closed). Fig. 2 is a section on the line II-II of Fig. 1 with the parts in open position. Fig. 3 is a similar section with the parts in the position occupied just as the die is ready to act upon the plate to be embossed. And Fig. 4 is another section similar to that of Figs. 2 and 3, but with the parts in completely closed stamping or embossing position.

Referring to the drawings, 1 is the bottom die holder in which is removably mounted the die plate 2, and 3 is the top die holder which carries the removable die plate 4. The bottom holder or member is provided with a handle 5 and with a transverse groove 6 which serves to position and hold the dies in the anvil or base in which the pair of die members, in company with a series of others, are mounted.

The member 1 is provided at its rear end with a pair of upstanding flanges 7, 7 between which is pivoted the rear end of the top member 3. Located between the die plates and the hinge connection between the die holders is a spring 8, which normally holds the die

members in open position, as indicated in Fig. 2, so that when the operating plunger which moves the top die member is retracted, the dies open, permitting the removal of the embossed plate and the insertion of a new blank. 55 The flanges 7, 7 act as a housing for the spring and their forward ends or shoulders act as stops for positioning the blank 9 to be pressed, as indicated in Figs. 1 to 3. The stop shoulders also serve as a protection against blanks 60 being accidentally pushed back against the spring and interfering with the action or injuring it.

The hinge connection between the die holder, which is the primary feature of novelty in 65 the construction, comprises a pivot pin 10, mounted at its ends in the flanges 7, 7, and a sleeve 11 journaled on the pin 10 and mounted for oscillation in the end of the top die member 3. The sleeve is slotted as indicated at 70 12 in Figs. 2, 3 and 4, the purpose being to provide a means for limiting the oscillating movement of the sleeve in the extreme positions shown in Figs. 3 and 4. The stop means for 75 limiting the oscillating movement is the screw 13.

When the die 1 is in the complete open position, the sleeve 11 occupies the position shown in Fig. 2. This position is maintained until the die reaches the position shown in 80 Fig. 3 with the upper die plate 4 having its face in engagement with the blank 9 which is to be embossed. At this time the die members 1 and 3 are in substantial parallelism, which parallelism will be maintained until 85 the stamping or embossing action is completed as shown in Fig. 4. When the operating plunger or platen which engages the top of the member moves down, carrying the member 3 from the position of Fig. 3 to the final 90 position of Fig. 4, the eccentric sleeve turns in a counter clockwise direction about the pin 10 from the position of Fig. 3 to that of Fig. 4. This lowering of the center line of the sleeve 95 permits the top die to move down maintained in parallelism with the bottom die throughout the stamping operation, that is, without any tilting action during such operation.

During the movement of the top die from the position of Fig. 3 to that of Fig. 4, such die 100

necessarily moves slightly to the left and back to the right due to the movement of the center line of the sleeve about the center line of the pin 10 as an axis, but this movement is very limited and has no unfavorable effect either upon the blank or dies. The first lateral movement to the left does not displace the blank since the end of the blank engages the ends of the flanges 7, 7 which thus act as gage means for positioning the blanks.

The operation as above described imposes little strain or wear upon the hinge parts which in service show no appreciable wear after long periods of use. At the same time the guiding function of the hinge parts obviates the use of guide shoulders or other guide means upon the opposing die members, such as have heretofore been required where hinged dies were associated for approach in parallel planes. The spring 8 is protected from injury, the ends of the flanges 7, 7 serving the dual function of positioning the blanks and protecting the spring from such blanks. Other advantages incident to the cheapness and simplicity of the construction and its positive action will be apparent to those skilled in the art.

What I claim is:

1. In combination in a die construction, a bottom die member, a top die member, and a hinge connection at the ends of the members comprising a sleeve mounted for oscillation in one of the members, means for limiting such oscillation, and a pivot pin extending through the sleeve eccentrically thereof and through the other of said members.

2. In combination in a die construction, a bottom die member, a top die member, a hinge connection at the ends of the members comprising a sleeve mounted for oscillation in one of the members, means for limiting such oscillation and a pivot pin extending through the sleeve eccentrically thereof and through the other of said members, and a spring between the die members intermediate the dies and the hinge connection for normally maintaining the members in separated position.

3. In combination in a die construction, a bottom die member, a top die member, and a hinge connection at the ends of the members comprising a sleeve mounted for oscillation in the top member, means for limiting such oscillation, and a pivot pin extending through the bottom member and through the sleeve eccentrically thereof.

4. In combination in a die construction, a bottom die member, a top die member, a hinge connection at the ends of the members comprising a sleeve mounted for oscillation in the top member, means for limiting such oscillation, and a pivot pin extending through the bottom member and through the sleeve eccentrically thereof, and a spring between the die members intermediate the dies and

the hinge connection for normally maintaining the members in separated relation.

5. In combination in a die construction, a bottom die member having a pair of spaced upstanding flanges at its rear end, a bottom die member, a hinge connection at the ends of the members comprising a sleeve mounted for limited oscillation in the top member, and a pivot pin extending through the sleeve eccentrically thereof and journalled at its ends in said flanges, and a spring lying between the members in the space between said flanges and normally maintaining the members in open position, the forward end of said flanges being located so as to act as a gage or stop for the plates which are positioned on the bottom die member.

6. In combination in a die construction, a bottom die member, a top die member, and a hinge connection at the ends of the members comprising a pivot pin mounted in the lower die member, and a member pivoted on the pin and also pivoted in the upper die member off center with respect to said pivot pin, permitting the upper die member to swing about the pivot pin as an axis and also to have an approximate parallel movement with respect to the lower member when such upper member approaches closed position.

In testimony whereof, I have hereunto subscribed my name this 30th day of January, 1932.

F. S. SPEICHER.
